UNITED STATES PATENT OFFICE

HARRISON HURLBERT BOYCE, OF NEW YORK, N. Y.

DESIGN FOR A MOTOR HEAT INDICATOR

Application filed October 16, 1931. Serial No. 41,408. Term of patent 14 years.

To all whom it may concern:

Be it known that I, HARRISON HURLBERT BOYCE, a citizen of the United States and a resident of the city, county, and State of New York, have invented a new, original, and ornamental Design for a Motor Heat Indicator, of which the following is a specification, reference being had to the accompanying drawings, forming a part hereof.

Referring to the annexed sheet of drawings:

Figure 1 is a front elevation of a motor heat indicator showing my new design;

Figure 2 is a side elevation; and

Figure 3 is a top plan view of the same.

I claim:

The ornamental design for a motor heat indicator substantially as shown.

HARRISON HURLBERT BOYCE.
